UNITED STATES PATENT OFFICE.

EDOUARD ERNEST LEHWESS, OF ST. CLOUD, NEAR PARIS, FRANCE.

PROJECTING MACHINE.

Application filed January 6, 1923. Serial No. 610,995.

This invention relates to feed mechanisms for projecting machines and more especially to that portion of the feed mechanism which produces an intermittent feed of a film strip 5 to bring successive pictures of the film in register with an aperture in the film gate, where, by any suitable arrangement of objective with a source of light, pictures are projected upon a screen in the well known 10 manner.

The mechanism is also suitable for the projection or display of glass slides conveyed by a belt or chain in sequence on a disc of glass or other suitable material; 15 where the movement of the pictures is intermittent and where the period of rest may be of short or long duration.

The particular embodiments of my invention are shown in the accompanying drawings in which—

Figure 1 is an elevation of one form of construction.

Figure 2 is a modified form of operating device partly in section that may be used 25 to actuate the shaft *a* in Fig. 1.

Figure 3 is an elevation of a further modified form and in particular shows the driving of the projector by a motor.

Figures 4 to 6 are details of construction 30 of the arrangement of the form of escape-
ment shown in Figure 3.

Referring to Fig. 1, there is mounted on shaft *a* an oscillating member *b* which is or embodies an armature of suitable form secured to the shaft *a*. A frame or support *v* and *v'* adjacent the armature has bearings to support the shaft *a* and has a stop *b'* 35 adapted to engage a cooperating stop *b''* associated with the armature so that the extent of oscillation of the armature, and therefore the shaft *a* is definitely predetermined and positively limited. A coil *c* has a core of any usual form with the bars or extensions *t* and *u* forming poles which 40 are energized by current passing through coil *c*. These pole pieces *t* and *u* extend into proximity of opposite sides of the armature *b*, so that energizing the pole pieces creates a magnetic field and forces 45 the oscillation of the armature *b* around its support until the stop *b''* engages the stationary stop *b'*. Such magnetic actuation turns the shaft *a* against the resistance of the spring *d*, so that when the current from 50 *r* is broken the spring *d* having been put in tension reacts to turn the shaft *a* back to

its initial position of engagement by the pin *h* with the pawl on the spool member *f*, and thereby oscillates the armature *b* back to its initial position. This provides for an uninterrupted oscillation of the shaft *a* a predetermined definite amount limited by the force imparted by the spring until the pin *k* passes over the pawl and catches it and with a positive limitation of stop *b'* 60 which prevents *b''* from passing in either direction, and a forward drive of the film or picture always the same definite extent, in order that it may provide a driving mechanism to assure positive feed of a definite section of film or definite individual slides or similar picture element. In Fig. 2 the driving mechanism may be replaced by the solenoid *c'* in which is mounted a cylinder *m* 70 of non-conducting material which guides a core *n* actuated by the solenoid *c'* connected with a link *o* to a crank *p* which is keyed or otherwise secured to the shaft *a* in Fig. 1.

Preferably at the end of shaft *a*, and in any event secured to it in a suitable position, 80 is a disc or flange *a'* which may carry a pin *h* adapted to engage a pawl *k* on a spool member *f* suitably fashioned with teeth *g* or the like, adapted to engage the perforations 85 on a film *e* in order to drive the film in known manner, or having teeth or other engaging means to engage a band, chain or the like to transmit step-by-step motion for the purposes of this projector. A gate *i* 90 may have projections *h* to guide in known manner the movement and predetermine definite position of the film. The spool *f* being driven at one end has at the other end a stop *k'* adapted to engage a pawl *k'* having a fixed support adjacent and mounted 95 in a manner whereby the predetermined oscillation of the spool in the driving direction is held by the pawl *k'* to prevent the spool from turning back when the shaft *a* with its driving connection turns back to its 100 initial position.

When the armature *b* is oscillated, the movement is produced by current in the coil *c* energizing the poles *t* and *u*, and a very slight current and momentary current 105 causes the complete swing around of the armature with a positive stop at the predetermined point. Low current consumption may be helped with particular forms of armature, and as shown part of the mass of the armature may be given an eccentric 110 position with respect to the shaft *a* so as to

reduce the inertia of starting by helping the magnetic action with gravity, and in turn when the reverse movement of the armature begins gravity may help the spring, 5 therefore assuring minimum size and strength of parts, smoothness and quickness of action. Thus the construction provides for the minimum strength of current required for the driving mechanism, and 10 this in turn reducing the strength of current at the contacts of make-and-break apparatus minimizes wear and prolongs the life, making the mechanism in practice more efficient and economical. As this class of 15 projector is intended for operating for long periods and automatic, it is of the greatest importance that the least possible attention and great durability of all parts determine superiority of the entire mechanism. Without 20 attendants, the clockwork *s*, or other suitable automatic means may be disposed in the circuit *r* leading to the coil *c* or the solenoid *c'*, so as to interrupt the current at predetermined periods or intervals.

25 The operation of the devices hereinbefore described is as follows:

When the circuit of the coil *c* or *c'* is closed by the clockwork or other suitable device the coil *c* will be energized so that 30 a magnetic field is produced between its poles *t* and *u* and the armature *b* will be oscillated through a predetermined fraction of a revolution. In the case of the modified mechanism in Figure 2 the solenoid *c'* is 35 energized, when the core *n* will be raised so as to rock a shaft *a*, which shaft is the spool driving shaft shown in Figure 1. In this modified form the fractional rotation of shaft *a* is to the extent of the throw of 40 the crank *p* actuated by the solenoid core or plunger *n* connected by link *o* with the crank *p*, and when the current is cut off the spring *q* pulls back the crank *p* to its initial position and pulls down the core to the bottom 45 of the solenoid, thus putting it in a position to repeat the next rotation step as soon as the circuit is again closed. The rocking movement of the shaft *a* causes a partial movement of the spool *f* which feeds the film, band, chain or the like the distance of one picture through the gate. After 50 the coils have been energized to produce the rocking movement of the shaft *a* as described the current to the coils will be interrupted, the spool will be held in its advanced position by the cooperation of *k'* and *k*, and while the shaft *a* returns to its initial position due to the ratchet connection *k* releasing from the spool, whereas the 55 ratchet *k'* on the other end of the spool holds the spool in its advanced position so that the film or the like remains stationary in the gate until the circuit is again closed by the clockwork and the armature or core 60 actuate the shaft *a* again for the fractional

predetermined revolution. When the current is interrupted the armature *b* is returned to its original position by the spring *d* whilst the core *n* is returned to its original position by the spring *g*. 70

The feeding mechanism may also be arranged as shown in Figures 3, 4 and 6, which show a modified form of step by step, or periodic advance of the pictures, by means of a motor driven by an electric current. 75 The shaft *a* is provided with teeth 1 which gear with a toothed wheel 2 formed integrally with a spring casing 4 mounted on a shaft 3. Adjacent the toothed wheel 2 there is loosely mounted on the shaft 3 a disc 5 80 provided with a number of pins 6. To the inner surface of the disc is secured one end of a spring 7 of which the other end is connected to the shaft 3. The shaft 1 is driven by a small motor 12^a through gearing 13 85 which drives the shaft *a* and this in turn through the toothed portion of the toothed wheel 2 drives the shaft 3. Rotatably mounted on the shaft *a* is a sleeve *a'* to which is secured a retarding disc 8 provided 90 with a notch 10. This retarding disc 8 normally engages with one or more of the pins 6 and thus prevents the rotation of the disc 5 so that when the shaft 3 is rotated the spring 7 will be tensioned. The disc 95 8 is also provided with a pin 11 projecting into the path of a radial pin 9 secured to the shaft *a*. As the shaft rotates the radial pin 9 will be brought into engagement with the pin 10 and thus turn the disc 8 so as 100 to bring the notch 10 opposite one of the pins 6. As soon as the pin 6 engages with the notch 10 the disc 5 is released and will be moved rapidly by the spring 7 and turn the disc 8. This movement of the disc 8 105 serves to advance the film or the like this being effected by means of forks or projecting members 12 provided on the sleeve *a'*. After the members 12 have moved the film through the required distance they disengage therefrom. On the further rotation of the shaft *a* the pin 9 is caused to catch up the pin 11, which has been moved in advance thereof by reason of the rotation of the disc 8 by means of the disc 5, and 110 will cause the disc 8 to be released from the pin 6 and lock the disc 5 against further movement so that the spring 7 will again be tensioned. The pin 9 remains in engagement with the pin 11 until the notch 10 is 115 again brought opposite one of the pins 6. These operations are continued so that the pins 6 of the disc 5 will be brought into operation successively.

In Figure 3, 14 indicates the lens which projects the images directly or by reflection by means of suitable mirrors to a suitable screen or other surface on which the image is to be observed.

In the modification shown in Figure 5 the 130

members 12 are replaced by friction segments 13^a which exert a slight pressure against the film *e* or the like which bears against a spring mounted roller 14^a or the like, thus providing for a driving engagement of the film by pressure between the segment 13^a and roller 14^a.

From the description of the relation of parts and their operation, it will thus be seen that in any of the forms, the mechanism guides a film or the like by feeding forward at a desired time interval readily predetermined, and that each step of the feed is quick and between feeds the film or the like is at rest and registers as predetermined with the gate, for the desired display. The mechanism is simple and particularly in the forms shown in Figures 1 and 2, it provides the means whereby actuating current need be used only for the short interval of forward drive, with no loss of current during the remainder of the time. The limited motion of the moving parts of the mechanism involve practically no wear, and the ratchet mechanism is of the simplest form with accuracy and positive drive, and besides the certainty of operation these parts as well as the rest of the mechanism can be made at small cost, with accuracy, and in all provide a durable and serviceable mechanism fully meeting all the requirements of such a projector step feed mechanism.

It will be understood that various modifications may be made without departing from the spirit of the invention. For example instead of using films, bands or the like post cards or small opaque objects may be arranged on polygonal rollers or the like which are adapted to be rotated intermittently in the manner hereinbefore described.

The apparatus described is particularly suitable for advertising purposes and may be adapted for use in conjunction with conditionally transparent mirrors on the back of which the object on the film or the like is projected or reflected. In the case of a transparent film any suitable illuminating means may be provided for projecting the images thereon on to the back of a conditionally transparent mirror. The circuit for the illuminating means may also be controlled by the clockwork so that whilst the film is being moved the mirror will act as an ordinary mirror whereas when the film is stationary the light will cause it to be projected on to the back of the mirror so that the image may be seen therein.

While various modifications may be made in detail and arrangement, and the inventions may be variously combined, otherwise than as hereinbefore shown and described, what I claim and desire to secure by Letters Patent is:

1. A feed mechanism for projecting apparatus wherein the feed of the film or other

pictures are suitably arranged for intermittent projection, comprising an automatic electric driving mechanism, means between the driving mechanism and the film strip or like picture mounting to effect alternately a quick feed of the film or like a predetermined and always uniform extent, said means including a spring cooperating with the electric drive, means to switch on a momentary current actuating the mechanism a substantial part of a revolution against the resistance of the spring, means for breaking the current and allowing return-motion by the spring energy to the initial or normal position.

2. A feed mechanism for projecting apparatus wherein the feed of the film strip or other image-supporting element suitably arranged for successive movement cooperates with intermittent moving mechanism, comprising an actuating shaft, an armature connected to rock said shaft, a coil to operate said armature, a fixed stop to resist the movement of the armature always at the same predetermined point in the forward driving direction, a circuit to energize the coil for rocking said shaft in one direction, means for intermittently making-and-breaking said circuit, and means between the actuating shaft and film strip or the like including a one-way driving connection and controlling means to uniformly advance each image a predetermined and always a fixed distance.

3. In projecting apparatus feed mechanism for intermittent still projection, a feed mechanism comprising a film sprocket or the like, a shaft and a one-way drive connection between said shaft and sprocket, electro-magnetic means connected with said shaft to oscillate the same in the driving direction a substantial part of but less than a whole revolution, a spring temporarily put in tension by the electrically operated means to return said shaft to its initial position and means for holding said sprocket or the like with its connected film always in a fixed uniformly advanced position when the one-way drive mechanism is released.

4. A feed mechanism for projecting apparatus adapted to provide intermittent motion and a stationary period for still projection, comprising film or picture drive connections, a shaft to drive the same including a one-way clutch, electro-magnetic means to oscillate said shaft quickly in one direction a predetermined distance and fixed means to uniformly limit the successive motions, a clutch for holding said sprocket stationary for the still interval, and a clock controlling the current to the electro-magnetic means to control the still intervals and periodic feed.

5. A feed mechanism for projecting apparatus wherein the feed of the film strip

or other picture supporting means is suitably arranged for successive movements, a rotating drive for the feed mechanism electrically actuated and a stop to arrest the rotation at a fixed point, a drive pin to rotate the feed mechanism a predetermined extent sufficient to completely displace always one image on the film strip or other picture support means, a reverse acting spring set in tension by the forward driving mechanism, means for cutting the current and interconnections to automatically return the feed mechanism to a predetermined point for initial starting of the drive.

15 6. A projecting apparatus wherein the

feed of the film strip or other picture-supporting means is arranged for successive movement under automatic control, comprising electrically actuated means to uniformly feed the film or the like positively and always the same forward uniform distance, means momentarily cutting in-and-out an electric current driving said electrically actuated means, and non-electrical means actuating the driving mechanism uniformly back 20 always to a predetermined initial position.

In testimony whereof, I have signed my name to this application this 14th day of December, 1922.

EDOUARD ERNEST LEHWESS.
